DRY CLEANER

Byron R. Winborn, Jr., Manitowoc, Wis., assignor to Manitowoc Shipbuilding Company, Manitowoc, Wis.

Application October 26, 1948, Serial No. 149,311

Term of patent 14 years

(CL D49—1)

To all whom it may concern:

Be it known that I, Byron R. Winborn, Jr., a citizen of the United States, residing at Manitowoc, in the county of Manitowoc and State of Wisconsin, have invented a new, original, and ornamental Design for a Dry Cleaner, of which the following is a specification, reference being had to the accompanying drawing, forming part thereof.

The figure is a perspective view of a dry cleaner showing my new design, the rear being substantially plain and the side not shown being substantially the same as the side shown.

I claim:

The ornamental design for a dry cleaner, as shown and described.

BYRON R. WINBORN, JR.
